TOOL VIBRATING MEANS

John E. Kline, Grosse Pointe Farms, and Douglas T. Peden, Ann Arbor, Mich., assignors to Micromatic Hone Corporation, Detroit, Mich., a corporation of Michigan

Application May 24, 1939, Serial No. 275,519

7 Claims. (Cl. 51—59)

Our invention relates to a grinding device and particularly to a unit device for reciprocating an abrading stone on the outer surface of a cylindrical element.

For the purpose of obtaining very accurate dimensions, contour, and finish on the surface of a cylindrical workpiece, a device is employed for changing a motion in rotation to one in translation for reciprocating an abrading stone longitudinally on the outer surface of a cylindrical workpiece. The device is preferably mounted in a standard which may be moved toward and away from a workpiece and to be fed therealong during the time the abrading stone is being reciprocated. The device may be attached to the table of a grinding machine adjacent to the grinding stone thereof to follow the grinding stone across the workpiece surface to perform a finishing operation as the surface is being rough finished by the grinding wheel.

The device embodies an eccentric shaft supported in a casing which in turn is supported by a housing containing a motor having a train of reduction gears associated therewith for driving the shaft in rotation. The eccentric end of the shaft projects into an end of a wobble arm which is supported medially of its length in a ball socket, with the extending end disposed to actuate a slide in reciprocation. An abrading stone is retained on the outer face of the slide for tilting movement by suitable spring means. The device rapidly reciprocates the abrading stone, and can be supported by hand to produce a finish on a cylindrical surface, but which is preferably supported in a standard and accurately adjusted relative to a surface, to not only produce a fine finish but also to machine to an accurate dimension.

Accordingly, the main objects of our invention are to provide a self-contained unit for driving an abrading element in reciprocation longitudinally of its length; to mount a unit element which drives an abrading stone in reciprocation on a standard which supports the element for axial adjustment; to mount a shaft having an eccentric on one end in bearings in a housing supporting a driving element which is attached to the opposite end of the shaft and connect a wobble arm to the eccentric for the purpose of changing a movement in rotation to one in translation; to provide a slide in the end of the tool to which the end of the oscillatable wobble arm is secured, having a support thereon for an abrading stone which permits the stone to tilt normal to the axis of the device; and in general, to provide a unit device for rapidly reciprocating an abrading stone axially,

which is simple in construction, positive in operation, and economical to manufacture.

Other objects and features of novelty of our invention will be specifically pointed out or will become apparent when referring, for a better understanding of our invention, to the following description taken in conjunction with the accompanying drawing, wherein:

Figure 1 is a side view of a device embodying features of our invention mounted adjacent to a grinding stone with its abrading end in contact with the workpiece to be finished;

Fig. 2 is an enlarged sectional view of the device illustrated in Fig. 1;

Fig. 3 is an enlarged sectional view of the structure illustrated in Fig. 2, taken on the line 3—3 thereof;

Fig. 4 is an enlarged sectional view of the structure illustrated in Fig. 2, taken on the line 4—4 thereof;

Fig. 5 is an exploded view in perspective of the left-hand end of the tool illustrated in Fig. 2; and

Fig. 6 is an enlarged sectional view of the structure similarly illustrated in Fig. 2, showing a modified form of the left hand end portion thereof.

The tool 10, illustrated in the figures, embodies a housing 11 in which a bearing supporting element 12 is retained by the threads 13. A roller bearing 14 abuts against the shoulder 15 at the lower end of the element, while an upper bearing 16 abuts against the shoulder 17 of the element. An oil seal 18 is mounted below the bearing 16 for sealing a shaft 19 which is supported by the bearings 14 and 16. The shaft has an enlarged end 21 on the left, as viewed in the figure, from which an angularly disposed crank arm 22 extends. The opposite end of the shaft has a threaded portion 23 on which a nut 24 is threaded for clamping the shaft to the inner raceways of the bearing.

40 A driving end 25 on the shaft has a keyway 26 into which projects a key 27 which is supported on a threaded collar 28 threaded upon the stub end 29 of a shaft 31 of a driving element 32. A lock nut 33 locks the threaded sleeve 28 to the shaft.

45 A housing 34 is attached to the right hand end of the housing 11 by a screw 35 which draws the sides of the split portion 36 about the housing 11. The opposite end of the housing 34 is split at 37 and is clamped about the housing of the driving element 32 by a screw 38. The driving element 32 is of conventional form having a motor 39 operating through a train of gears 41 for reducing the speed developed by the motor when rotating the shaft 19, while increasing the driving torque.

50 On the left hand end of the housing 11, a

wobble arm 42, having a semi-spherical portion 43, is supported in a collar 44, having a semi-spherical mating aperture 45 which receives portions 43 of the arm. A spring 46 is retained on the arm by a pin 47 which urges the semi-spherical portion 43 into the aperture. The upper end of the arm has pinned thereto a bifurcated element 48, the ends 49 of which have cylindrical surfaces 51. A raceway 52 of truncated spherical form is received within with the surfaces 51 and contacts the end of the crank arm 22 through bearings 53 of the needle type. The raceway 52 is supported by the surfaces 51 through the adjustment of a screw 54 which draws the bifurcated ends 49 toward each other. The arrangement is such that the resistance imparted to the raceway 52 by the cylindrical surfaces 51 is greater in the plane of oscillation of the arm 42 and of a lesser degree in a plane transverse thereto. The guides 42' maintain the oscillating movement of the arm 42 in a fixed plane. The degree of wobble or oscillation to the arm 42 is adjusted by changing the longitudinal position of the crank arm or pin 22 through the adjustment of the sleeve 12 in the casing 11. This adjustment changes the effective radius of the crank arm or pin to increase or decrease the effective circles described thereby.

The lower end of the wobble arm 42 terminates in a ball 56 which is disposed in an aperture in a slide 58. The slide is provided with projecting flanges 61 which operate in slots 62 in the end of a sleeve 63 having a shoulder 65 supported against the end of the housing 11 by a flanged nut 64. A pin 66 projecting from the enlarged end portion 67 of the sleeve 63 extends within a slot 68 in the end of the housing for positioning the sleeve thereon. The slide engages a block 71 having projecting flanges 72 which extend over the faces 73 of the slide to form a driving connection therewith. The opposite face of the block has arcuate end portions 74 which engage the annularly disposed surfaces 75 on the backing element 76 of the abrading stone.

The slide 58 has a side wall slotted at 78 in which side projecting portions 79 on the backing element 76 project to provide a driving relation therebetween. The side projecting portions 79 have the portion in engagement with the wall 78 of arcuate shape to permit the backing element to tilt on the arcuate surfaces 74 and the face of the stone to adjust itself relative to the surface of the workpiece. Projecting fingers 81 extend from the slide 58 and from the backing element 76 which are connected by springs 82 for supporting the backing element on the slide while permitting the tilting of the element on the block.

In Fig. 6 we have illustrated a slightly modified form of wobble element 85 supported between the guides 85' directly in the housing 86, which is similar to the housing 11 above described. The end of the sleeve 86 is slotted at 87 and has arcuate elements 89 secured to the side walls. The elements 89 and the edge 90 of the housing are provided with slots 91 in which the projecting flange 61 of the slide 58 is supported for movement in reciprocation or vibration. An annular collar 92 is slidably disposed within the end of the housing 86 and has a truncated spherical aperture 93 which receives the spherical portion 43 of the wobble arm 85. A spring 94 is supported in the housing on a

washer 95 retained in position by a clamping ring 96. The spring urges the annular sleeve 92 upwardly to provide a spring support for the wobble arm. Otherwise, the device is the same as that illustrated and described relative to Figs. 1 to 5, inclusive.

The device just described produces a fast reciprocation in the order of a vibration to an abrading stone, axially of its length. A movement in rotation from a driving motor, which is part of the unit, is changed to one in reciprocation through a shaft having an eccentric end engaging a wobble arm. By selecting the proper train of gears, by regulating the length of the wobble arm on either side of its pivot point, or by varying the speed of the motor, the speed of vibration of the abrading stone in reciprocation may be adjusted. Mounting means may be provided for the self-contained device which is preferably adjustable to move the device axially toward and away from the work. The adjustable support is preferably mounted on a bed which may be raised and lowered and moved toward and along the workpiece. While the device may be supported by hand, such mounting means is more desirable so that the workpiece may be accurately machined to a desired dimension.

While we have described and illustrated but two embodiments of our invention, it will be apparent to those skilled in the art that various changes, omissions, additions, and substitutions may be made therein without departing from the spirit and scope of our invention, as set forth in the accompanying claims.

We claim as our invention:

1. A unit device for oscillating a machining element embodying a casing, a shaft rotatably journaled in the casing, an eccentric end on said shaft, a wobble arm in extension of said end oscillated thereby, a slide mounted in said casing for reciprocation by said wobble arm, and means for supporting said machining element on said slide.

2. A unit device for oscillating a machining element embodying a casing, a shaft rotatably journaled in the casing, an eccentric end on said shaft, a wobble arm in extension of said end oscillated thereby, a slide mounted in said casing for reciprocation by said wobble arm, means for supporting said machining element on said slide, and motor means carried by said casing and connected to said shaft.

3. A unit device for machining the surface of a workpiece embodying a casing, a rotatable shaft journaled therein, motor means carried by said casing for driving said shaft in rotation, a machining element supported by said casing for movement in reciprocation, and means aligned with said shaft and interconnecting said machining elements with said shaft for changing the movement in rotation to one in reciprocation of said element.

4. A unit device for machining the surface of a workpiece including, in combination, a casing, a shaft having an eccentric end journaled in said casing, a wobble arm supported inter-jacent its ends in extension of said shaft for universal movement having a driving connection with eccentric, a slide reciprocally supported in said casing and connected to said wobble arm, and a machining element supported on said slide for tilting movement.

5. A self contained tool embodying a motor, a casing supporting said motor, a shaft driven

in rotation by said motor, a slide supported for reciprocal movement by said casing, means in extension of said shaft interconnecting said slide and shaft to change a movement in rotation of the shaft to one of reciprocation of the slide, and an abrading element supported on said slide, the contact between said slide and element being such as to permit said element to tilt relative to said slide.

6. A self-contained tool embodying a casing; a rotatable shaft in said casing, a crank arm on said shaft disposed at an angle thereto, a wobble arm mounted in said casing oscillating

5 in said crank arm, and means for moving said shaft axially to change the effective radius of the crank arm which varies the degree of oscillation of said wobble arm.

7. A self-contained tool embodying a casing; a rotatable shaft in said casing, a crank arm on said shaft disposed at an angle thereto, a wobble arm mounted in said casing oscillating in said crank arm, and a slide reciprocally mounted in said casing and joined to one end of the wobble arm.
